US00D850417S

(12) **United States Design Patent** (10) Patent No.: **US D850,417 S**
(45) Date of Patent: ** Jun. 4, 2019

(54) **EAR HOOK**

(71) Applicant: **SHENZHEN GINTO E-COMMERCE CO., LIMITED**, Shenzhen (CN)
(72) Inventor: **Yong Yang**, Shenzhen (CN)
(73) Assignee: **Shenzhen GINTO E-Commerce Co., Limited**, Shenzhen (CN)

(**) Term: **15 Years**

(21) Appl. No.: **29/623,227**

(22) Filed: **Oct. 24, 2017**

(51) LOC (11) Cl. **14-01**
(52) U.S. Cl.
USPC **D14/223**

(58) **Field of Classification Search**

(57) **CLAIM**

The ornamental design for an ear hook, as shown and described.

DESCRIPTION

FIG. 1 is a perspective view of an ear hook showing my new design;
FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is perspective view of the ear hook mounted to an earbud.
The broken lines showing an earbud in FIG. 9 depict environmental subject matter only and form no part of the claimed design.

1 Claim, 9 Drawing Sheets
